US0D1079737S

(12) **United States Design Patent** (10) **Patent No.:** **US D1,079,737 S**
(45) **Date of Patent:** **** Jun. 17, 2025**

(54) **DISPLAY SCREEN WITH GRAPHICAL USER INTERFACE**

(71) Applicant: **BELING XIAOMI MOBILE SOFTWARE CO., LTD.**, Beijing (CN)

(72) Inventor: **Wei Zhang**, Beijing (CN)

(**) Term: **15 Years**

(21) Appl. No.: **35/518,660**

(22) Filed: **Sep. 25, 2023**

(80) **Hague Agreement Data**

Int. Filing Date: **Sep. 25, 2023**

Int. Reg. No.: **DM/232007**

Int. Reg. Date: **Sep. 25, 2023**

Int. Reg. Pub. Date: **Oct. 13, 2023**

(30) **Foreign Application Priority Data**

Apr. 18, 2023 (CN) 202330214399.3

(51) **LOC (15) Cl.** **14-04**

(52) **U.S. Cl.**

USPC **D14/486**

CLAIM

The ornamental design for a display screen with graphical user interface as shown and described.

DESCRIPTION

2. Display Screen with graphical user interface

3. Display Screen with graphical user interface

4. Display Screen with graphical user interface

8. Display Screen with graphical user interface

2.1 : Front View

3.1 : Front View

4.1 : Front View

8.1 : Front View

The portions of the graphical user interface shown in broken lines form no part of the claimed design. The broken line showing of a display screen forms no part of the claimed design.

1 Claim, 4 Drawing Sheets
